(57) **CLAIM**

The ornamental design for a tamper evident security seal, as shown and described.

DESCRIPTION

FIG. 1 is a perspective view of a tamper evident security seal in accordance with the present invention;

FIG. 2 is another perspective view of the tamper evident security seal of FIG. 1;

FIG. 3 is a front elevation of the tamper evident security seal of FIG. 1;

FIG. 4 is a rear elevation of the tamper evident security seal of FIG. 1;

FIG. 5 is a side elevation of the tamper evident security seal of FIG. 1;

FIG. 6 is an opposite side elevation of the tamper evident security seal of FIG. 1;

FIG. 7 is an end elevation of the tamper evident security seal of FIG. 1; and,

FIG. 8 is an opposite end elevation of the tamper evident security seal of FIG. 1.

The broken lines in the drawings are for illustrative purposes only and form no part of the claimed design.
